UNITED STATES PATENT OFFICE.

JOHN L. SCHAD, OF FORTUNA, MISSOURI, ASSIGNOR OF ONE-HALF TO OLIVER W. CARTER, OF FORTUNA, MISSOURI.

RATCHET-WRENCH.

No. 858,030.

Specification of Letters Patent.

Patented June 25, 1907.

Application filed February 9, 1907. Serial No. 356,622.

To all whom it may concern:

Be it known that I, JOHN L. SCHAD, a citizen of the United States, residing at Fortuna, in the county of Moniteau and State of Missouri, have invented a new and useful Ratchet-Wrench, of which the following is a specification.

This invention has relation to ratchet wrenches and it consists in the novel construction and arrangement of its parts as hereinafter shown and described.

The object of the invention is to provide a ratchet wrench which is devoid of spring actuated pawls and which may be easily and quickly adjusted for turning objects in either direction. The wrench is therefore substantial in its construction and avoids the use or employment of delicate parts and consequently may be used for heavy work and will retain its durability for a comparatively long period of time.

The wrench consists primarily of a stock having at one end a handle grip and at its opposite end a head. A pivot is mounted upon said stock. A shaft is journaled for rotation upon the head of the stock and is provided with a gear wheel and a non-circular end. A detachable socket fits over the non-circular end and is held thereon by means of a set screw or similar securing device. A ratchet member is mounted upon the pivot of the stock and is provided at one end with a handle grip and at its other end with laterally disposed shoulders which operate as pawls for engaging the gear wheel of the shaft on either side of the longitudinal axis of the stock. The distance between the pivot upon the stock and the periphery of the gear wheel is greater than the length of the pawl member from the point where it is mounted upon said pivot to the end upon which is located the handle grip. Consequently, the handle grip end of the ratchet member may be swung or passed between the pivot and the gear wheel in order that the ratchet end of the said member may be brought in contact with either side of said gear wheel. By this arrangement the wrench may be used for turning objects in either direction.

In the accompanying drawing:—Figure 1 is a side elevation of the wrench. Fig. 2 is an edge elevation of the same with parts in sec-

tion, and Fig. 3 is a transverse sectional view of the work engaging end of the wrench. 55

The wrench consists of the stock 1 upon one end of which is located a handle grip 2. Said stock is provided at its other end with a head 3. The pivot pin 4 is attached to the stock 1 at a point between the ends thereof, 60 Said pin is provided with a lug 5 which is disposed toward the end of the stock 1 having the head 3. The shaft 6 is journaled in the head 3 and is retained therein by the screw 7. Said shaft is provided with a gear wheel 8 and a non-circular end 9. The socket 10 is provided with an opening for the reception of the non-circular portion 9 of the shaft 6 and is also provided with an opening in its opposite end for the reception of a nut or tap to be 70 turned. The said socket is retained in position upon the end 9 of the shaft 6 by a set screw 11 which passes transversely through the socket and engages the portion 9 of the said shaft. Other suitable means may be 75 employed for adjustably or removably attaching the socket to the shaft 6 the idea being that sockets having openings for the reception of nuts of different sizes or shapes may be interchangeably applied to the shaft 80 6 in order to meet requirements. The pawl member 12 is provided at one end with a handle grip 13 and at its opposite end with the laterally disposed shoulders 14, 14 which constitute pawls and which are adapted to engage the gear wheel at either side of the longitudinal axis of the stock 1. The pawl member 12 is provided with a perforation 15 which receives the pivot 4 and said perforation 15 is provided in its side with a recess 16 through 85 which the lug 5 passes when the pawl member 12 is mounted upon the stock 1. The recess 16 is disposed toward the end of the member 12 which is provided with the handle grip 13 and consequently extends in a direction 90 substantially opposite to the lug 5 when either one of the shoulders 14 is in engagement with the gear wheel 8. As the distance from the pivot 4 to the gear wheel 8 is greater than the distance from the perforation 15 to 100 the end of the member 12, having the handle grip 13 the said end of the member 12 may be swung between the pivot 4 and the gear wheel 8 so that either one of the shoulders 14 may 105 be brought into engagement with the said gear wheel. Thus it is obvious that the said

pawls may be so moved as to prevent the rotation of the gear wheel 8 in one direction but permit its rotation in the opposite direction. Furthermore, in order to apply or remove the member 12 from the pivot 4 the handle end of the said member is brought into alinement with the stock 1 and lies between the pivot 4 and the gear wheel 8 when the said member 12 may be readily lifted off of the pivot 4 the lug 5 thereof passing through the recess 16 of the perforation 15.

Having described my invention what I claim as new and desire to secure by Letters-Patent is:—

15 A wrench comprising a stock having at an intermediate point a pivot pin and at one end

a handle stock, a ratchet socket member journaled for rotation at the opposite end of the stock, a pawl member detachably journaled upon the pivot pin and lying in a plane parallel with the stock and having at one end a handle grip and at its opposite end, laterally disposed shoulders separated by an intervening projection.

In testimony that I claim the foregoing as my own, I have hereto affixed my signature in the presence of two witnesses.

JOHN L. SCHAD.
